UNITED STATES PATENT OFFICE.

ELI H. CRUM, OF CLOVERBEND, ARKANSAS.

BACK-BAND BUCKLE.

SPECIFICATION forming part of Letters Patent No. 707,394, dated August 19, 1902.

Application filed May 24, 1901. Serial No. 61,763. (No model.)

To all whom it may concern:

Be it known that I, ELI H. CRUM, a citizen of the United States, residing at Cloverbend, in the county of Lawrence and State of Arkansas, have invented certain new and useful Improvements in Back-Band Buckles; and I do hereby declare the following to be a full, clear, and exact description of the invention, such as will enable others skilled in the art to which it appertains to make and use the same.

My invention relates to back-band buckles and securing device for trace-chains; and my object is to provide a device of the character specified which will be found to be reliably efficient in the performance of its office, the same being readily and adjustably secured in place upon the back-band.

The details of my invention will be clearly set forth in the following specification, and illustrated in the accompanying drawings, of which—

Figure 1 is a perspective view illustrating my invention as applied to use. Fig. 2 is a perspective detail view of my back-band buckle complete. Fig. 3 is a longitudinal section thereof. Fig. 4 is a perspective view of one end of my back-band attachment, showing a portion thereof separated from parts with which it coöperates.

In order to conveniently refer to the several features of my invention and their co-operating accessories, numerals will be employed, of which—

1 indicates the back-band of the usual or any preferred construction, to which I attach my adjustable trace-holding device, consisting of the end sections 2 and 3 and the bottom section 4, rigidly attached to said end sections or integrally formed therewith, as preferred. I have shown the bottom section 4 in Fig. 3 as being an integral sleeve-like extension of the end sections 2 and 3, properly cast or otherwise extended around a reinforcing-rod, said sleeves being cut away or removed at their middle portion to provide a seat or journal to be received by an aperture in the upper end of the securing-hook 18. The upper ends of the end sections 2 and 3 are provided with suitable apertures, in which I rotatably dispose the trunnions or journals 5, formed upon the back-band-engaging member 6, said member being provided with a longitudinally-

disposed slotted opening 7, as clearly shown in Figs. 2, 3, and 4. I prefer to extend one of the journals 5, so as to provide the flattened extension or handle portion 8, the outer end of the opposite journal being also extended, as indicated by the numeral 9, said extension being provided with a recess adapted to loosely receive the upper end of the locking detent 10, the lower end of which is pivotally secured to the extension 11, formed upon the section 4 or upon the outer face of the end section 2. The extension 11 is provided with a recess, as indicated by the numeral 12, adapted to receive the lower end of the detent 10, said detent being held in its operative position by a suitable rivet 13.

In order to dispose the upper free end of the detent 10, normally in contact with the end section 2, I extend the lower end of the detent sufficiently below the extended end 11, as indicated by the numeral 14, to permit it to be engaged by the spring 15, which is located in a suitable recess provided in the contiguous portion of the end section 2. In order that the detent may be readily grasped and withdrawn from its recess in the extension 9, I provide the handle or extended end 17. By reference to Fig. 3 it will be observed that the outer end of the detent 10 may be drawn outward entirely out of engagement with its recess in the extension 9, when the handle 8 may be grasped and the member 6 rotated in order that any slack in the back-band may be taken up or compensated for, as desired.

Having thus described the construction of my improved back-band attachment, the operation or manner of using the same may be stated to be as follows: The back-band, of any suitable flexible material, may be provided in the usual manner with means for fastening the same upon the animal after the band shall have been extended through the slot 7 provided in the rotatable member 6, and in order that the attachment may be secured at the desired point on the back-band the member 6 is rotated, which will cause the back-band to be wound around it, thereby insuring that the device will be securely held in place and also that the slack in the back-band will be taken up by winding the band around said member.

Pivotal secured to the section 4, prefer-

ably near the middle portion thereof, is the securing-hook, as indicated by the numeral 18, said hook being adapted to engage the tug or trace-chain 19, as shown in Fig. 1.

5 While I have described the preferred construction which may be adopted in materializing my invention, it will be understood that I desire to comprehend in this application all substantial equivalents and substitutes which 10 may be considered to fall fairly within the scope of my invention.

Believing that the advantages and construction of my improved back-band attachment have been made fully apparent from 15 the foregoing specification, considered in connection with the accompanying drawings, further reference to the details thereof is deemed unnecessary.

What I claim as new, and desire to secure 20 by Letters Patent, is—

1. The herein-described back-band attachment comprising the frame members 2, 3 and 4 rigidly secured together, a slotted member 6 rotatably mounted in the end members of 25 said frame; an extension 9 formed on the end of said rotatable member and provided with a recess in its end, combined with an outwardly-movable detent adapted to engage said recess and means to normally hold the 30 detent in place whereby when said detent is withdrawn the rotatable member 6 may be turned to release or tighten the back-band, all substantially as specified and for the purpose set forth.

35 2. The herein-described back-band attach-

ment comprising the end sections 2 and 3, and the member 4 rigidly connecting said end sections combined with the member 6 having the longitudinally-disposed slot rotatably mounted in said end sections and provided at one 40 end with a handle portion 8 and at the opposite end with the recessed extension 9, and a spring-controlled detent normally held in engagement therewith whereby the upper end of said detent will rest in the recess provided 45 in the extension 9 and may be manually withdrawn therefrom as desired, all substantially as specified and for the purpose set forth.

3. A back-band attachment comprising a suitable frame-section combined with a slotted 50 rotatable member 6, carried in the frame and having an operating-handle at one end extending outward from the frame and provided with the extension 9 upon the opposite end said extension 9 being provided with a recess 55 in its extreme end, and a detent pivoted upon the outer side of the frame and having its free end extending into said recess combined with a suitable spring to hold the free end of the rotatable member 6 may be adjustably secured by means of said handle and said operating detent, all combined substantially as specified and for the purpose set forth.

In testimony whereof I affix my signature 65 in presence of two witnesses.

ELI H. CRUM.
